GEARING

Oliph M. Knight, Chicago, Ill., and Warren C. Le Mire, Miami, Fla.; said Le Mire assignor to Frank J. Kraemer, Pottsville, Pa.

Application May 24, 1941, Serial No. 395,083

4 Claims. (Cl. 74—422)

This invention relates to speed controlling devices and more particularly to an improved governor.

One object of the invention is to provide a governor which is operated by centrifugal force and which will, when operatively connected with the generator of an internal combustion engine, effectively control the speed of rotation of the crank shaft of said engine.

Another object of the invention is to provide a device of this character which will, when operatively connected with the speedometer shaft of a motor vehicle, control the rolling speed of said vehicle.

A further object of the invention is to provide a governor wherein adjusting means is employed for controlling response so that said governor may be caused to operate at any desired speed of the shaft to which it is connected.

Still another object of the invention is to provide a speed controlling device of this character which is characterized by simplicity in construction and efficiency in operation.

And another object of the invention is to provide a governor which may be quickly attached to the intake manifold of an internal combustion engine.

Still further objects of the invention will become apparent as the description thereof proceeds.

In the drawings forming a part of our application:

Figure 1 is a horizontal sectional view, partly in elevation, showing our improved governor as it would appear mounted on the intake pipe or throat of an internal combustion engine.

Figure 2 is a front elevation of the governor as it would appear in operative position, the cover plate being removed to show the rack and pinion and bracket construction, and

Figure 3 is an enlarged detail perspective view of the bracket employed for supporting the free end of the rack.

In the drawings like numerals of reference designate like parts throughout the views. The numeral 1 indicates the intake pipe or throat of an internal combustion engine. The pipe 1, as shown, is of the type used in connection with a dual carburetor. However, it should be understood that the invention is adapted for use with the intake pipes of single carburetors. Rotatably mounted in the pipe 1 is a transversely extending shaft 2, said shaft extending diametrically of the intake openings 3 and 4 of the

pipe. Mounted on the shaft within the intake openings are butterfly valves 5 and 6.

In carrying our invention into effect, we employ a housing 7 which is formed of cast metal or other suitable material. The housing 7 has integrally formed thereon a reduced substantially rectangular extension 8, said extension being formed with an end wall 9 and a rear wall 10. The housing 7 also includes a hollow cylindrical body 11 which is formed with an end wall 12, to which the extension 8 is connected, and an end wall 13. The end wall 12 is formed with an axial internally threaded opening 14 into which is screwed a bearing plug 15, said bearing plug being formed with a bearing recess 16. The end wall 13 is formed with an exteriorly threaded boss 17 and said boss is formed with an axial opening 18 in the inner end of which is mounted a bearing plug 19 having a bearing recess 20 therein. The opening 18 is aligned with the opening 14 so that the recesses 16 and 20 will also be aligned. As best seen in dotted lines in Figure 2, the body 11 of the housing 7 is formed with an opening 21, the purpose of which is to permit ready observation or adjustment of the mechanism, to be described hereinafter, which is contained within said body. A cover plate 22 normally closes the opening 21 and is held in place by means of screws 23.

The rear wall 10 of the extension 8 of the housing 7 is formed, substantially medially of its length and height, with an opening 24 which receives the outer end of the shaft 2 therethrough, said shaft extending into the area of the said extension. A bushing 25 surrounds the shaft and extends into both the flattened surface of the pipe 1 and the flat rear surface of the wall 10. Mounted on the outer end portion of the shaft 2 is a pinion 26, said pinion being held to rotate with said shaft by a nut 27. Normally closing the front of the extension is a removable cover plate 28, said plate being held in position by means of screws 29. Bolts extend through the rear wall 10 and operatively connect the device with the pipe 1.

Rotatably mounted within the body 11 of the housing 7 is a governor shaft 30. The shaft 30 is formed with a reduced outer end portion 31 which defines a conical bearing surface 32. The outer end portion 31 extends through the plug 19 and said bearing surface is engaged by a plurality of ball bearings 33 which are carried in the recess 20. A cap 34 surrounds the shaft 30 and closes the open end of said recess 20. As will be clearly seen in Figure 1, the reduced portion 31

extends into the opening 18 of the boss 17 and is flattened to define a coupling element 35. The coupling element is to be connected with a similar coupling element on the end of a flexible shaft, the opposite end of said flexible shaft being operatively connected either to the generator shaft or to the speedometer shaft, depending upon the purpose for which the governor is to serve. The opposite end of the shaft 30 is reduced to define a conical bearing surface 36 which is disposed within the recess 16 of the bearing plug 15 and is engageable with ball bearings 37 in said recess. A ring 38 surrounds the end portion of the shaft and closes the open end of said plug. In order to lock the plug against accidental rotation, we provide a lock nut 39.

The shaft 30 is formed with a bore 40 which extends from the inner end of said shaft throughout the major portion of its length and which communicates with a slot 41 which extends diametrically of the shaft, said slot being located near the outer end of the shaft. Slidably mounted within the bore 40 and extending into the slot 41 is a plunger 42. The plunger 42 is enlarged to define a cup 43 in which cup is mounted a ball bearing 44.

Our improved governor includes weights 45 and 46 which are disposed within the body 11 of the housing 7 and are pivotally connected with a collar 47 by means of pins 48. The collar is held to rotate with the shaft 30 by means of a set screw 49. Slidably mounted on the shaft 30 and normally disposed about the slot 41 is a sleeve 50. Surrounding the sleeve is a collar 51 which is pivotally connected with the outer end portions of the weights 45 and 46 by means of links 52. Extending through the collar 51 and the sleeve 50 and through the slot 41 is an operating pin 53, the mid-portion of said pin normally engaging the outer end of the plunger 42 which, as stated, extends into the slot 41. Surrounding the mid-portion of the shaft 30 and confined between the inner end of the sleeve 50 and the inner end of the collar 47 is a compression spring 54, said compression spring normally urging the sleeve 50 and collar 51 rearwardly for swinging the weights 45 and 46 toward the shaft 30.

Although a more complete description of the operation of our invention will be set forth in more detail hereinafter, it is desired to state at this time that, when the shaft 30 is rotated at a predetermined rate of speed, the weights 45 and 46 will swing outwardly, by centrifugal force. When this takes place, the sleeve 50, the collar 51 and the pin 53 will be shifted along the shaft 30 toward the collar 47 against the tension of the spring 54. When this takes place, the plunger 42 will be advanced within the extension 8 for operating the butterfly valve shifting mechanism now to be described.

The butterfly valve operating mechanism per se is mounted within the extension 8 and, as best seen in Figure 2, includes a rack 55 which is substantially square in cross section and which extends longitudinally of said extension. The rack 55 is formed with rack teeth 56 and a guide shank 57. The rack also includes a threaded inner end portion which is shown in dotted lines at 58. The rack teeth 56 are, of course, engaged with the teeth of the pinion 26 so that, when said rack is shifted longitudinally within the extension, the pinion will be rotated for rotating the shaft 2. Screwed on the threaded inner end portion 58 of the rack is a cap 59 which is of hardened metal and which is provided with a flat end face 60 for

engagement with the ball 44 in the cup 43. Lock nuts 61 and 62 are also screwed on the threaded portion 58 and serve to lock the cap in an adjusted position. In order to movably support the inner end portion of the rack 55, we provide a bracket 63 which is adjustably connected with the wall 10 of the extension 8 by a bolt 64, said bracket having a slot 65 through which the bolt extends. The bracket also includes a supporting element 66 which extends beneath the rack and, as stated, movably supports said rack.

The guide portion 57 of the rack 55 is slidably mounted in a guide lug 67 on a guide and adjusting bracket 68 which is shown in perspective in Figure 3 of the drawings. The guide and adjusting bracket 68 includes, in addition to the lug 67, a base 69 in which is formed a longitudinally extending slot 70. The outer end portion of the base is turned at right angles to define an arm 71 which is formed with a threaded opening 72. The arm 71 is disposed in parallel and offset spaced relation to the lug 67 which is, of course, also disposed at right angles to the base substantially medially of its length. As best seen in Figures 1 and 2 of the drawings, the guide and adjusting bracket is adjustably mounted on the wall 10 of the extension 8 by means of a screw 73 which extends through the slot 70 and into said wall 10. An adjusting screw 74 is screwed through the opening 72 and has its end normally in engagement with the inner surface of the end wall 9. A lock nut 75 is carried on the screw for locking said screw in an adjusted position.

Mounted on the inner end of the portion 57 of the rack 55 is a stop washer 76, said stop washer being held against inward movement on the rack by means of a stop pin 77. Surrounding the portion 57 of the rack between the washer 76 and the inner surface of the lug 67 is a compression spring 78. The spring 78 acts against the washer 76 and urges the rack inwardly for engaging the surface 60 of the cap 59 with the ball bearing 44 in the cup 43 at all times.

The operation of this invention will now be set forth. As stated at the beginning of our specification, our governor may be used either for controlling the speed of rotation (R. P. M.) of the crank shaft of the engine or for controlling the speed of the vehicle over the ground. In the first case, the governor is connected with the generator shaft and in the second case said governor is connected with the speedometer shaft. The operation of the invention is identical in either case. Suffice it to say that rotative movement is supplied to the governor shaft 30 through the coupling element 35. As explained hereinbefore, when the shaft 30 rotates at a predetermined rate of speed, the weights 45 and 46 will, by centrifugal force, cause the plunger 42 to be advanced within the extension. Inasmuch as the cap 59 is in engagement with the ball 44, the rack 55 will be shifted by movement of said plunger for rotating the pinion 26 and swinging the butterfly valves 5 and 6 to closed position for shutting off fuel flow through the pipe 1 when said predetermined speed has been reached.

Should it be desired to cause the governor to respond at a lower speed, the screw 73 is loosened and the screw 74 is retracted. After this is done, the guide and adjusting bracket is shifted toward the wall 9 with the result that the tension of the spring 78 will be reduced and the pressure of the rack against the plunger likewise reduced. When resistance against the plunger is reduced, the weights will become effective at a lower rate

of speed of rotation of the shaft for advancing said plunger and shifting the rack.

If, on the other hand, it is desired that the governor be held inoperative until after the shaft has been caused to rotate at a high rate of speed, the screw 73 is loosened and the guide and adjusting bracket is shifted toward the pinion 26 with the result that the spring 78 will be placed under greater tension. After this has been done, the lock nut 75 is loosened and the screw 74 is rotated until the end thereof again engages the wall 9. The bolt 73 and the lock nut 75 are again tightened for locking the bracket in this position. When the spring is held under greater tension, the rack will be urged against the ball bearing 44 with enough tension to prevent advance of the plunger until after the shaft 30 has been caused to rotate at a predetermined high rate of speed. In other words, the pressure of the cap 59 against the ball 44, which pressure is caused by the tension of the spring 78, will serve to overcome the centrifugal force tending to swing the weights 45 and 46 outwardly until the shaft 30 has been caused to rotate at a speed high enough for the centrifugal force to overcome the tension of said spring 78 when, of course, the plunger will be advanced against the tension of said spring for rotating the pinion and swinging the butterfly valves to closed position.

Our invention is characterized by the utmost simplicity in construction. Moreover, in view of the particular construction employed, it is thought that our improved governor would be highly efficient in use.

Although our invention is particularly adapted for use in conjunction with automobiles, it will lend itself for use with motor vehicles of all types.

Having thus described the invention, what is claimed as new is:

1. A governor including a housing having a side wall provided with an opening for introduction of a rotatable shaft carrying a pinion, a rack in the housing having teeth for meshing with the pinion and rotating the shaft when the rack is slid longitudinally, said rack having a guide portion, a stop washer on the guide portion of the rack, a cap on the opposite end of the rack, a plunger slidably mounted in the housing, a bracket in the housing having a guide lug slidably supporting the guide portion of the rack, a spring surrounding the guide portion between the lug and the stop washer and urging the rack longitudinally in a direction for engaging the cap with the plunger, and means in the housing for shifting the plunger, cap and rack against the tension of the spring for rocking the pinion and rotating the shaft.

2. A governor including a housing formed with an opening for introduction of a shaft carrying a

pinion, a rack in said housing having teeth for meshing with the pinion and rotating the shaft, a bracket in said housing having a lug slidably supporting one end portion of said rack, said bracket being formed with a longitudinal slot, a screw passing through said slot and mounting and mounting the bracket for longitudinal adjustment, an abutment upon said rack, a spring about said rack engaging the abutment and said lug and yieldably resisting longitudinal movement of the rack in one direction, and means in said body for acting upon the other end of said rack and shifting the rack longitudinally in opposition to the action of said spring.

3. A governor including a housing formed with an opening for introduction of a shaft carrying a pinion, a bracket in said housing formed with a longitudinally extending slot and having a laterally extending perforated lug and a laterally extending arm formed with a threaded opening, a screw passing through said slot and securing said bracket in adjusted position, a rack in said housing having teeth for meshing with the pinion and rotating the shaft when the rack is shifted longitudinally, a spring about said rack for yieldably resisting movement of the rack longitudinally in one direction having one end abutting said lug, a screw threaded through the opening of said arm for engaging a confronting portion of the housing and shifting the bracket to adjusted position, and means in said housing for acting on said rack and shifting the rack longitudinally in opposition to action of said spring.

4. A governor including a housing formed with an opening for introduction of a shaft carrying a pinion, a rack in said housing having teeth for meshing with the pinion and rotating the shaft, a bracket in said housing having a lug slidably supporting one end portion of said rack, said bracket being formed with a longitudinal slot, a screw passing through said slot and mounting the bracket for longitudinal adjustment, an abutment upon said rack, a spring about said rack engaging the abutment and said lug and yieldably resisting longitudinal movement of the rack in one direction, a second bracket in said housing disposed vertically and formed with a vertical slot, a roller carried by the second bracket and engaged under said rack to support the rack, a screw passed through the slot of the second bracket to secure the same in a vertically adjusted position with the roller in supporting engagement with the rack, and means in said housing for acting on an end of said rack and shifting the rack longitudinally on opposition to the spring to rotate the pinion and shaft.

OLIPH M. KNIGHT.
